[57] ABSTRACT

This invention relates to a combined, pneumatic, mechanical and electrical control timer mechanism including an air timer unit which comprises a resilient diaphragm having its outer periphery fixedly attached to said casing a compression spring mounted in the interior of said casing so as to urge resiliently said diaphragm in its inflating direction, an opening bored through said casing for establishing fluid communication between the interior space of said casing, the ambient atmosphere, and a pervious member covering said opening for limiting fluid passage through said opening, and a check valve means provided on said casing for checking invasion of ambient atmosphere from outside into the interior of said casing, yet, allowing the reverse air flow. The mechanism comprises further a cam shaft which carries a first, a second and a third cam. The third cam is an operation instructing member for control of a separate machine or instrument, such as the medicament sprayer. The first and second cams control a normally closed contact pair which is inserted in the circuit in the circuit for an electric motor geared to said cam shaft. The second cam is arranged to reset the air timer unit. The first cam acts upon the contact pair to open only after the second cam has completed the reset operation for the air timer unit.

CAM OPERATED RETARDED TIMER SWITCH ASSEMBLY WITH DASHPOT TYPE AIR TIMER UNIT

This invention relates generally to timers. More specifically, it concerns with a timer mechanism with an air timer unit, said mechanism being adapted for use in various fields, such as, for instance, intermittent spraying of dosed quantities of fungicidal liquor on the culturing field.

Conventional timers comprise frequently as the time control unit a mechanical or electric timepiece having a driver, preferably in the form of a power spring or an electric motor. In other known timer mechanisms, they operate by the way of thermal response. Others operate by gravity, fluid pressure or the like.

The use of power spring, however, invites a troublesome and frequent winding-up operation. With use of the commercial current source, a local and independent utilization of the timer, for instance on the culture fields may be frequently impossible.

It is therefore the main object of the present invention to provide an operation control timer devoid of the aforementioned conventional drawback. More specifically, it is aimed at by the present invention to provide an operation control timer of a simple design and arrangement having a self-contained power source or battery, in combination with a d.c. motor as the drive means and in combination with an air-operated time control unit.

The term "air timer unit" as used herein throughout the specification and appended claims means such a type of timer which comprises a resilient diaphragm having its outer periphery fixedly attached to said casing, a compression spring mounted in the interior of said casing so as to urge resiliently said diaphragm in its inflating direction, an opening bored through said casing for establishing fluid communication between the interior space of said casing, the ambient atmosphere, and a pervious member covering said opening for limiting fluid passage through said opening, and a check valve means provided on said casing for checking invasion of ambient atmosphere from outside into the interior of said casing, yet allowing the reverse air flow. The pervious member can be made of paper sheet, foam resin mass, cellophane sheet, porous sintered alloy mass, textile fiber mass, felt sheet, porous ceramic mass or the like.

A salient feature of the mechanism according to the present invention resides in that during the limited time interval, such as several tens minutes as an example, any power source such as current source, power spring or the like, is not operated and the power is consumed only for the resetting job. The energy dissipated during the resetting period is preserved in spring means contained in the timer unit. The release of the thus accumulated spring energy is braked by limiting the air invasion from outside of the timer unit through a highly limited fluid passage barrier such as pervious sheet, porous mass, or the like, into the interior of said timer unit. The reset drive mechanism comprises an electric motor, a current source connected therewith, a cam shaft operatively connected with said motor and carrying thereon three cams. When the cam shaft is rotated by actuation a main switch inserted in the motor circuit, the first one of said cams operates upon the diaphragm-spring combination of the air timer unit so as to reset

the latter through a certain intermediate member preferably formed into a first lever. A pair of switch contacts are provided in the motor circuit, the movable one of said contacts being mechanically connected with the diaphragm so as to be on-off controlled thereby.

The second cam operates through a second intermediate member, preferably made into a lever, on the movable contact.

10 The configurations and operational phases of these two cams are so selected that the timer unit has been reset so as to depress the diaphragm-spring combination to its most-compressed position and to exert its effort to displace the movable contact to its off-position, 15 the second cam acts upon the contact so as to maintain nevertheless the contact at its on-position for the time being, yet to bring it in its off-position after lapse of a certain initial presetting period. By bringing the movable contact into its interrupted position, the motor circuit is kept in off-service in spite of the on-position of the main switch.

20 A certain prescribed time interval has elapsed, the air timer unit is brought into the actuating position upon consuming the accumulated spring energy devoid of the initially loaded energy. Upon actuation of the timer unit so as to close the electric contacts for initiation of the rotational movement of the cam shaft by energization of the motor circuit, the third cam is brought into its actuation so as to perform an operation control job 25 for initiation of the operation of a certain instrument, machine, or the like.

30 These and further objects, features and advantages of the invention will become more apparent when read the following detailed description of the invention by reference to the accompanying drawing illustrative substantially of a preferred sole embodiment of the invention.

In the drawing :

35 FIG. 1 is a schematic sectional view of a time control unit employed in the operation control timer mechanism according to the invention positioned, however, in its reset position.

40 FIG. 2 is a similar view to FIG. 1, illustrative, however, of the unit in its operational position.

45 FIG. 3 is a schematic perspective view of an operation control timer as a whole, embodying the principles of the invention.

50 FIG. 4 is a timing chart showing mutual operational phases of several working parts of the mechanism shown in the foregoing.

55 Referring now to the accompanying drawing, the time control unit, generally shown at 7, comprises a diaphragm piston 1 which has a flexible diaphragm disc 1a and a thickened central part 1b, said parts being made integral with each other and the whole being made of a resilient and unpervious material such as soft rubber, plastics or the like.

60 Numeral 3 represents a rigid housing of unit 7, being made into a dish-shaped member which is made preferably of metal, hard plastic or the like. The housing 3 is formed at its top with an inwardly directing peripheral flange 3a for detachably fastening the peripheral zone of the diaphragm disc 1a by inserting under pressure a spring clip 6 formed into an open ring. Or alternatively, 65 a male-screwed cap may be used upon forming female screw threads on the upper portion of the inside peripheral wall surface of the housing 3, although not shown.

In this way, air chamber 5 is formed in the interior space of the unit 7, by being defined by the diaphragm piston 1 and substantial part of the inside wall surface of the housing 3, as shown.

A coil spring 2 is provided within the interior or air space 5 and between the central thickened part 1b of the diaphragm piston and the bottom 3b of housing 3, for urging the diaphragm in its inflating and expanding direction.

Between the opposing ends of the spring clip 6, there is provided with a gap which is normally closed by a part of the peripheral zone of the diaphragm, so as to form a check valve 26 thereat, as will be more fully described hereinafter. However, if necessary, a separate check or non-return valve means may be provided through the wall of housing 3, for allowing air discharge therethrough during the reset period to be set forth.

At the center of the housing bottom 3b, there is provided a fluid passage opening 25 which is surrounded with ample idle gaps by a barrier holder 27 which is fixed to the housing bottom 3b by set screws, glueing or the like conventional means although not shown. A small inside space 27a is formed within the holder 27 and contains a piece of a pervious material which provides a substantially air flow limiting or barrier effect when air flow is allowed to pass therethrough as will be more fully described hereinafter. A passage bore 29 is drilled through the barrier holder 27 so as to establish air flow from the ambient atmosphere into the air chamber 5 and in the reversed sense as occasion may desire to be more specifically described. The material for the barrier piece was already referred to hereinbefore by way of example.

In the mechanism shown in FIG. 3, an electric drive motor 11 is provided and connected electrically through battery 21 and main switch 22 with a pair of electrical contacts 9 and 10, so as to provide a motor circuit as shown. Contact 9 is a movable one, while contact 10 is a stationary one although its fixedly mounting means have been omitted from the drawing only for simplicity.

The drive motor 11 has a motor shaft 11a which is mechanically coupled through a reduction gearing, generally shown at 12, with a cam shaft 13 carrying three cams 14, 15 and 16 and rotatably mounted in end bearings 30 and 31.

The first cam 14 of the said three cams is arranged to act upon a follower lever 17 which is pivotably mounted at an intermediate point 32 between its opposite ends. The movable contact 9 is shaped substantially into a resilient tee and made of a resilient material and having a left hand arm 9b and a right hand arm 9a, the outer end of the former arm being kept normally in pressure contact with the tip end of the first lever 17, preferably through an insulating sheet positioned between the both, although not shown. The first end of lever 17 which is kept in contact with the first cam 14 is urged by a coil or pressure spring 33, as shown.

Second cam 15 is arranged as shown, to actuate upon a second switch lever 8 which is pivotably mounted at 19 and fitted with a tension spring 23 provided at a proximity to the related cam.

The outer end of arm 9b is kept in contact with the top end of the thickened central portion 1a of the diaphragm piston 1 by the tip end of second switch arm 8. With air timer unit 7 positioned in advance of resetting and with the first and second cams 14 and 15 having

their respective cam rise portions 14a and 15a positioned at their off-service position as shown, the stationary and movable contacts proper "A" and "B" carried on respective tip ends of contact members 10 and 9, respectively, are kept in their mutually closed position. The dimensions and arrangements of several parts related with the switch contacts "A" and "B", and those of the air timer unit 7, especially the diaphragm piston 1 and spring 2, are selected to satisfy this requirement. This off-service position of the unit 7 is shown in FIG. 2 and that of the whole mechanism is shown in FIG. 3, respectively. The spring force at 23 is selected to be substantially smaller than that at 2.

The timing diagram of several working parts is shown in FIG. 4 as an example.

The operation of the mechanism so far shown and described is as follows :

With the operational parts positioned in FIGS. 2 and 3, the main switch 22 is now closed manually. Since both contacts proper "A" and "B" are closed with each other, current is conveyed from current source 21 to drive motor 11 and thus, the latter is caused to rotate.

Motion is now transmitted from drive motor 11 through gearing 12 to cam shaft 13. With rotation of cam shaft 13, and during the initial portion of the cam shaft rotation, the third cam 16 which is mechanically or mechano-electrically with a certain machine, such as a medicament sprayer by way of example, the operation of which is to be controlled by the mechanism according to this invention, delivers a certain instruction signed to the machine. As an example, the machine is actuated to initiate a spraying operation by being pushed down its actuating push button.

With further rotation of cam shaft 13, the cam rise portion 14a is brought into pressure contact with the root end of first switch lever 17, thus the tip end thereof being raised in its position. Therefore, the contact arm 9a is flexed resiliently, while the contacts proper "A" and "B" are kept in closed position.

Next, second cam 15 is brought into actuation so that the second switch lever 8 is depressed by contact with cam rise portion 15a, thereby the tip end of said lever depressing the diaphragm piston 1 and the spring 2 of timer unit 7 for performing the resetting operation therefor. Upon completion of this resetting operation, second cam rise portion 15a is brought into separation from contact with second switch lever 8. The unit 7 now takes the position shown in FIG. 1. During this resetting operation, the contacts proper "A" and "B" are kept in contact as before. Only after lapse of a certain short time period, the first cam rise portion is receded from contact with the related switch lever 17, so as to separate contacts proper "A" and "B" from each other for de-energizing the motor circuit.

The rotation of cam shaft 13 is terminated upon performing substantially a complete revolution thereof.

The duration period of the operation instruction signal delivered under the action of third cam 16 can be terminated at a proper time depending upon the cam configuration thereof, and in advance of the de-energization of the motor circuit.

During the presetting period, air will escape through the non-return valve formed at 26.

Upon completion of the resetting operation for the unit 7 in the aforementioned way, the preset and thus compressed-down diaphragm spring combination will recover gradually its original non-compressed state, the

necessary time period for such full recovery depending upon the size of the opening 29 and the degree of perviousness of the material at 28. This member 28 can be, when necessary, attached fixedly to the bottom surface of the lower wall 3b, so as directly to cover the passage at 25. In this case, the member 27 can be removed from the mechanism.

The aforementioned on-off control operations can be repeated until the main switch 22 will have been intentionally cut off by the operator. During this repeated on-off control operation, operation control signals by the action of the third cam 16 will be delivered repeatedly at regular time intervals corresponding to the recovery periods of the said diaphragm and spring combination.

Although not shown only for simplicity of the drawing, the mechanism shown in FIG. 3 comprises a stationary housing member which supports rigidly the several members of the mechanism, such as those shown at 10, 11, 19, 23, 30, 31, 32 and 33. This housing is provided with an intermediate and perforated bottom 100 only partially shown, which supports the air timer unit 7 stationarily, as clearly seen from FIGS. 1 and 2.

For completeness, the movable switch 9 is pivotably supported at its root end, as schematically shown at 101 in FIG. 3.

I claim:

1. An operation control timer mechanism comprising an air timer unit, a rotatable cam shaft carrying first, second and third cam means rigidly thereon, an electric motor operatively connected to said shaft having circuit means including a power source and switch means comprised of a stationary contact and a movable contact, a first switching arm means operably disposed between said movable contact and said first cam means for periodically engaging said movable contact to close said switch means, and a second switching arm means operably disposed between said movable contact and said second cam means for periodic movement to a position allowing said movable contact to open said

40

switch means, said third cam means being adapted to control a timed output response, said air timer unit being comprised of a casing, a resilient diaphragm having an outer periphery fixed to said casing, a compression spring mounted in the interior of said casing so as to resiliently urge said diaphragm outwardly from said casing, an opening bored through said casing for establishing fluid communication between the interior of said casing and the ambient atmosphere, a pervious member covering said opening for limiting fluid passage through said opening, and check valve means provided on said casing allowing only air flow from the inside of said casing to the outside thereof, said diaphragm being disposed in engagement with said second switching arm adjacent said movable contact member for normally biasing said movable contact member to close said switch means under the influence of said spring, said second cam means adapted to periodically shift said second switching arm to compress said spring and allow said movable contact member to open said switch means with said first cam means and said first switching arm are not holding said movable contact in a position to close said switch means.

2. An operation control timer mechanism as set forth in claim 1 wherein said first switching arm is pivoted intermediate the ends thereof with one of said ends being disposed in operative engagement with said movable contact and spring means biasing the other of said ends into operative engagement with said first cam means.

3. An operation control timer mechanism as set forth in claim 1 wherein said second switching arm is pivoted at one end thereof with the opposite end being disposed between said flexible diaphragm and said movable contact, said second switching arm being disposed for engagement by said second cam means at a point intermediate the ends of said arm and spring means normally holding said arm in engagement with said flexible diaphragm.
